UNITED STATES PATENT OFFICE

105,094

DESIGN FOR TEXTILE FABRIC

Curt Erwin Forstmann, Montclair, N. J.

Application September 21, 1935, Serial No. 58,658

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing forming part thereof.

In the drawing, the sole figure of which is a plan view of a piece of the textile fabric embodying the design of the present invention, the cloth depicted is of a single color.

The design is a three-dimensional surface ornamentation of parallel diagonal elevated stripes composed of coarse broad kinky loops and nodes, irregularly laid, giving the stripes irregular lateral edges which substantially obliterate the background between the stripes, giving only a suggestion of background.

I claim:

The ornamental design for textile fabric as shown and described.

CURT ERWIN FORSTMANN.
